TELEVISION ANTENNA

Mel Appel and Martin Schnur, West Orange, N.J.
(both of 87 Woodland Road, Short Hills, N.J. 07078)

Filed Sept. 27, 1965, Ser. No. 87,174

Term of patent 14 years

(Cl. D26—14)

FIG. 1 is a front elevational view of a television antenna, showing our new design;

FIG. 2 is a right side elevational view, the left side being substantially a mirror image thereof;

FIG. 3 is a rear elevational view; and

FIG. 4 is a top plan view thereof.

The dominant features of our design reside in the portion shown in full lines.

We claim:

The ornamental design for a television antenna, as shown and described.
